(57) **CLAIM**

The ornamental design for a hook wall mount for a portable media playback device as shown and described.

DESCRIPTION

FIG. 1 is a front elevation view of a hook wall mount for a portable media playback device, according to a third embodiment;

FIG. 2 is a rear elevation view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof; and,

FIG. 8 is another perspective view thereof.

The dashed broken lines in the figures illustrate portions that form no part of the claimed design.
